GARMENT

Joseph Henry Schweich, Clayton, Mo.

Application May 9, 1938, Serial No. 206,707

1 Claim. (Cl. 2—224)

The present invention relates generally to garments, and more particularly to undergarments generally referred to as panties.

An object of the present invention is to provide an undergarment having a seat portion adapted to conform to the body of a wearer.

Another object is to provide an undergarment which is adapted to fit the nether portion of a wearer in a manner to permit ready bending and twisting movements.

Another object is to provide an undergarment which is adapted to conform to the nether portion of the human body when the wearer is standing in a manner to prevent bunching of material, yet which does not bind when the wearer bends over.

Another object is to provide an undergarment of the pantie type which is of two-piece construction and which includes a novel seat portion.

Another object is to provide an undergarment which includes a seat piece of a material and so disposed relative to the remainder of the garment to provide maximum stretch longitudinally of the body of a wearer and minimum stretch transversely thereof.

Another object is to provide an undergarment having leg portions having stretch completely therearound while retaining the longitudinal stretch of the body portion of the crotch.

Another object is to provide an undergarment which is seamless in that area which lies adjacent the sensitive parts of a wearer.

Another object is to provide an undergarment which is easily made, which includes a minimum 35 of seams, thereby adding to comfort, and which is relatively inexpensive to fabricate.

Other objects and advantages will be apparent from the following description, taken in conjunction with the accompanying drawing, in which:

40 Fig. 1 is a front view of a pair of panties constructed in accordance with the teachings of the present invention;

Fig. 2 is a rear view of the pair of panties shown in Fig. 1;

45 Fig. 3 is a section on the line 3—3 of Fig. 2;

Fig. 4 is a section on the line 4—4 of Fig. 2;

Fig. 5 is a section on the line 5—5 of Fig. 2;

Fig. 6 is a view of a piece forming the main body portion of the panties shown in Fig. 1, the 50 said piece being in outspread relation to clearly disclose critical curves; and,

Fig. 7 is a view of the second piece of the panties shown in Fig. 1, which forms the seat portion thereof, the piece being outspread to properly disclose critical curves.

Referring to the drawing more particularly by reference numerals, 10 indicates a pair of panties constructed in accordance with the concepts of the present invention. The pair of panties 10 comprises a main body piece 11 and a seat piece 12.

The main body piece 11 is preferably of the configuration shown in Fig. 6, and includes end edges 13 and 14 which are convex throughout substantially the full extent thereof. Each edge 10 includes a notch 15 for a purpose to be described. An upper edge 16 includes two intersecting straight segments 17. A lower edge 18 is of irregular contour and includes oppositely disposed straight segments 19 and 20, and straight segments 21 which form a V-wedge, a work notch 22 being provided at the juncture of the segments 21.

The seat piece 12 is preferably of the configuration shown in Fig. 7, and is symmetrical about 20 the dotted line 25, being defined by opposed straight edges 26, a concave edge 27, and intersecting edges 29, each of which includes two straight segments 30 and 31 joined by an intermediate concave segment 32.

In Figs. 1 and 2 the pieces 11 and 12 are shown in assembled form. A waist band 33 of elastic material is connected to the top edge 16 in a manner to pucker the material adjacent thereto.

In the assembled garment 10 the edge 27 is connected to the edges 21 by stitching 34 (Fig. 4), the notch 22 being closed over the central portion thereof. The edges 29 are connected to the edges 13 and 14 by stitching 35 (Figs. 3 and 4), the edges 29 extending up to the notches 15, which are closed over the point effected by the intersection of the said edges 29. Above the notches 15 the edges 13 and 14 are connected by stitching 36 (Fig. 5). The segment 19 of the lower edge 18 of the piece 11 and one edge 26 of the piece 12 form the lower boundary of one leg, and the segment 20 of the edge 18 and the other edge 26 form the lower boundary of the other leg. The edges forming the lower boundary of the legs are rolled back and secured by stitching 37. The edges are, 45 of course, turned inwardly to provide a smooth exterior. It is therefore, apparent that the garment 10 is seamless in that area which lies adjacent to and contacts the sensitive parts of the body of a wearer. Hence, no injury or irritation, often caused by seams rubbing thereagainst, can arise.

In order to secure a sturdy garment the seat portion is reinforced by the use of two pieces 12 which are, of course, superposed and assembled, 55

for all practical effects, as a single piece. In the preferred seat piece a material is employed which permits maximum stretch longitudinally of the body of a wearer and minimum stretch laterally thereof.

- 5 It is apparent from an inspection of Figs. 1 and 2 that the seat portion of the garment bags in a manner to provide space for the seat of a wearer. This suitable and ample bagging is effected by 10 the cut of the edges 13, 14, and 29. The concave segments 32 are of sharper curvature than the convex edges 13 and 14. Therefore, the edges 29 must be crowded into alignment with the edges 13 and 14 during the stitching operation. 15 In effect, a flare is caused which materializes in the full or bulged seat. A smooth seat fit is thus provided without causing bunching in the leg portions. The construction achieved has been found to be eminently satisfactory.
- 20 The broad principles of the present invention are shown exemplified by a pair of panties, but it is to be understood that they can readily be embodied in other garments requiring a fullness in the seat.
- 25 It is apparent that there has been provided an undergarment which fulfills all of the objects and

advantages sought therefor. It is to be understood that the foregoing description and accompanying drawing have been given by way of illustration and example and not for purposes of limitation, the invention being limited only by 5 the claim which follows:

What is claimed is:

A garment comprising an integral main body piece symmetrical about a center line including lateral edges of convex contour and a V-notch in 10 the lower edge, and an integral seat piece symmetrical about a center line including similarly disposed concave straight edges each of which comprises an inwardly located concave portion and straight line portions, said seat piece further including another edge of substantially the combined length of the edges of the V-notch in the main body piece, said concave straight edges of the seat piece being connected to said convex edges of the body piece and the said another edge of the seat piece being connected to the edges of the V-notch of the main piece, whereby fullness 15 of the seat without undue sag and correct leg fit obtain.

JOSEPH HENRY SCHWEICH. 20
